UNITED STATES PATENT OFFICE

91,720

DESIGN FOR AN OPEN COCKPIT PURSUIT AIRPLANE

Charles N. Monteith, Robert J. Minshall, and John Kylstra, Seattle, Wash., assignors to Boeing Airplane Company, Seattle, Wash., a corporation of Washington

Application December 22, 1932, Serial No. 46,572

Term of patent 14 years

To all whom it may concern:

Be it known that we, CHARLES N. MONTEITH, ROBERT J. MINSHALL, and JOHN KYLSTRA, citizens of the United States residing at Seattle, in the county of King and State of Washington, have invented a new, original, and ornamental Design for Open Cockpit Pursuit Airplanes, of which the following is a specification, reference being had to the accompanying drawings, forming part thereof.

Figure 1 is a plan view of the airplane, Figure 2 is a front elevation thereof, Figure 3 is a side elevation, all in the attitude of flight, and Figure

4 is a three-quarter front perspective view, from above.

We claim:

The ornamental design for an open cockpit pursuit airplane, as shown.

Signed by said MONTEITH and KYLSTRA at Seattle, King County, Washington, this 3rd day of December, 1932.

CHARLES N. MONTEITH.
JOHN KYLSTRA.

Signed by said MINSHALL at Dayton, Montgomery County, Ohio, this 12 day of December, 1932.

ROBERT J. MINSHALL,
